UNITED STATES PATENT OFFICE

130,821

DESIGN FOR A RADIO RECEIVING SET

Daniel J. Crowley, Grosse Pointe, Mich.

Application February 3, 1941, Serial No. 98,709

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Radio Receiving Set, of which the following is a specification, reference being had to the accompanying drawing, forming a part thereof. The single figure in the drawing is a front perspective view of a radio receiving set showing my new design.

The side of my new design for a radio receiv-

ing set opposite the front side shown in the drawing and the adjacent sides are substantially the same in appearance with the exception that the window in the front side for exposing the station indicating dial is omitted from the rear and adjacent sides of the tuning member.

The dominant features of my design are shown in full lines in the drawing.

I claim:

The ornamental design for a radio receiving set, substantially as shown and described.

DANIEL J. CROWLEY.
